US00D857724S

(12) **United States Design Patent** (10) **Patent No.:** **US D857,724 S**
Clediere et al. (45) **Date of Patent:** **** Aug. 27, 2019**

(54) **DISPLAY PANEL OF A PROGRAMMED COMPUTER SYSTEM WITH A GRAPHICAL USER INTERFACE**

(71) Applicant: **Facebook, Inc.**, Menlo Park, CA (US)

(72) Inventors: **Robin Maxime Clediere**, San Francisco, CA (US); **Kory Matthew Westerhold**, Palo Alto, CA (US); **Christopher Joseph Welch**, Menlo Park, CA (US)

(73) Assignee: **Facebook, Inc.**, Menlo Park, CA (US)

(**) Term: **15 Years**

(21) Appl. No.: **29/630,843**

(22) Filed: **Dec. 22, 2017**

(51) LOC (12) Cl. **14-04**

(52) U.S. Cl.

USPC **D14/486**

(58) **Field of Classification Search**

(57) **CLAIM**

What is claimed is the ornamental design for a display panel of a programmed computer system with a graphical user interface, as shown and described.

DESCRIPTION

FIG. 1 is a face view of a first embodiment of a display panel of a programmed computer system with a graphical user interface; and,

FIG. 2 is a face view of a second embodiment of the display panel of a programmed computer system with a graphical user interface.

The broken lines in the drawings are included for the purpose of illustrating environmental structure and form no part of the claimed design.
